(57) **CLAIM**

The ornamental design for a roam fishing reel, as shown and described.

DESCRIPTION

FIG. 1 is a front perspective view of the roam fishing reel showing my design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken lines in the Figures are for the purpose of illustrating the environment in which the design is associated and form no part of the claimed design.

1 Claim, 8 Drawing Sheets

FIG. 2

FIG. 3

FIG. 4

FIG. 5

FIG. 6

FIG. 8
